UNITED STATES PATENT OFFICE.

MADGE WICKHAM-VON KÖPPE, OF NEW YORK, N. Y.

DESIGN FOR A PIN.

SPECIFICATION forming part of Design No. 36,174, dated December 23, 1902.

Application filed September 17, 1902. Serial No. 123,787. Term of patent 14 years.

To all whom it may concern:

Be it known that I, MADGE WICKHAM-VON KÖPPE, a resident of New York, in the county and State of New York, have invented a new, 5 original, and ornamental Design for a Pin, of which the following is a specification, reference being had to the accompanying drawing, forming a part thereof.

The accompanying drawing represents the 10 design which embodies my invention.

The leading feature of my design consists in a scarf-pin which comprises a heart, the jeweled pin rising from the apex of the heart and extending downwardly from its point, 15 an ornamental arrow whose rear portion projects upwardly from the left-hand top portion of the heart, while the arrow-point, which is

integral therewith, extends opposite thereto on the lower right-hand portion of same.

The drawing illustrates my ornamental pin, 20 in which 1 represents the heart, 2 2 represent the pin, 3 represents the jewel, 4 illustrates the rear portion of the arrow, and 5 is the arrow-point.

Having thus described my invention, I 25 claim—

The ornamental design for a pin substantially as herein shown and described.

In testimony whereof I affix my signature in the presence of two subscribing witnesses. 30
MADGE WICKHAM-VON KÖPPE.
